UNITED STATES PATENT OFFICE

151,327

DESIGN FOR AN AIRPLANE

Raymond C. Coates, Wesleyville, Pa.

Application April 2, 1947, Serial No. 138,112

Term of patent 14 years

(Cl. D71—1)

To all whom it may concern:

Be it known that I, Raymond C. Coates, a citizen of the United States, residing at Wesleyville, in the county of Erie and State of Pennsylvania, have invented a new, original, and ornamental Design for an Airplane, of which the following is a specification, reference being had to the accompanying drawings, forming part thereof, and in which drawings:

Figure 1 is a top plan view of an airplane, showing my new design;

Figure 2 is a side elevational view of the same;

Figure 3 is a bottom plan view;

Figure 4 is a front elevational view; and

Figure 5 is a rear elevational view.

I claim:

The ornamental design for an airplane, as shown.

RAYMOND C. COATES.
